Application February 6, 1948, Serial No. 6,747

4 Claims. (Cl. 248—125)

1

This invention relates to laboratory apparatus and more particularly to a device for holding laboratory equipment such as beakers, flasks, and the like.

In modern chemical laboratory operations, glass beakers of varying sizes from below 10 ml. capacity to above 4 liters are frequently employed as containers for storing, mixing, heating, transferring and reacting various chemical mixtures and compounds. As the size of the beaker increases, it becomes more difficult to manipulate, e. g. with beakers of low volume capacity, tongs may be employed to manipulate the beaker but when larger beakers are employed, especially those having a capacity of a liter or more the use of tongs becomes impractical due to both the increased size of the beaker and to its increased weight which is due mainly to the larger volume of its contents.

This problem is very serious when the beaker is employed with a laboratory stirrer. When high speed stirring is used, there is a tendency for the beaker to move due to the vibratory action of the stirrer. This may cause the wall of the beaker to come in contact with the stirrer blade and cause the breakage of either the stirrer or the beaker or both. A further problem is the difficulty of transporting and performing manipulating movements such as pouring with large beakers which are filled with hot and/or dangerous contents. Another problem is that when beakers with their contents are heated, there is a tendency for "bumping" of the contents with consequential movement of the beaker.

This invention has an object to provide a device for holding laboratory equipment such as beakers.

A further object is to provide a device for permitting laboratory equipment such as beakers to be clamped to a laboratory ring stand.

A still further object is to provide a device for permitting laboratory equipment such as beakers to be heated. Other objects will appear herein-after.

These and other objects are accomplished by the following invention in which there is provided a device for holding laboratory apparatus comprising a base having means for permitting the application of heat to said apparatus, a frame mounted on said base, the frame having means for holding said apparatus above said base and means for clamping said device to a suitable support.

An illustrative embodiment of the invention is shown in the accompanying drawing, in which:

Fig. 1 is a side elevational view of the present device clamped to a laboratory stand with a beaker held therein, the contents of said beaker being heated by a laboratory burner and agitated by a laboratory stirrer;

2

Fig. 2 is a perspective view of the invention with a beaker in dotted lines held therein;

Fig. 3 is a sectional view on the line 3—3 of Fig. 1;

Fig. 4 is a sectional view on the line 4—4 of Fig. 1;

Fig. 5 is a vertical section of a form of the means embodied in the present invention for clamping said device to the laboratory support.

With reference to Figure 1, the present invention **10** is shown connected by clamping means **12** through the use of a suitable laboratory clamp **14** to laboratory stand **16**. The beaker **18** held in place by means of the present invention is being heated by laboratory burner **20** and the contents of the beaker are being agitated by stirring rod **22** which is attached by chuck **24** to laboratory stirrer **26**.

Referring to the drawing as a whole, invention **20** **10** comprises circular base **28** having as shown in Figure 4, an annular heating aperture **27**. On base **28** is mounted a frame comprising a plurality of vertical bars **29, 30, 31, 32, 33** secured to the base **28** by horizontal flanges **34** welded to the base **28**. The vertical bars **29, 30, 31, 32, 33** are joined together at their upper extremities by an upper arcuated horizontal member **11** which extends from vertical bar **29** to vertical bar **33** but does not join vertical bar **29** to vertical bar **33**. Median horizontal member **36** joins vertical bars **29** and **33** at a place approximately half-way between base **28** and the lower edge of arcuated member **11**. Both horizontal members **11** and **36** are secured to the vertical bars by welds. The fact that arcuated member **11** does not extend for the full periphery of the top extremity of vertical bars **29** to **33** permits the facile pouring of the contents of beaker **18** through beaker lip **19**. On vertical bars **29, 31, 33** are mounted means for holding the beaker in position. These holding means comprise three units, each unit comprising, as shown for the unit on vertical bar **33**, two spring actuated members with the lower member comprising disc **37**, stud **38**, and spring **39**, and the upper member comprising disc **41**, stud **42** and spring **43**. These members acting in combination actuate holding leaf **40**. The three units functioning through holding leaves **40, 44, 46** hold beaker **18** in position and together form the holding means.

As shown in Figure 5 there is mounted on vertical bar **31** an arcuate member **11** a detachable clamping means **12** having a threaded projection **9** which is screwed into threaded socket **8**. Hence alternative clamping means having a different form than clamping means **12** given in Figure 5 may be inserted in lieu thereof.

Attached to vertical bars **29** and **30** is handle **50** wrapped with asbestos sheet **52**. On vertical bars **32** and **33** there is also attached a similar handle **51** wrapped with asbestos sheet **53**.

If desired an asbestos centered wire gauze 54 may be inserted by passing it between vertical bars 29 and 33 and under holding leaves 40, 44, 46. The lateral edges 56 and 58 of the asbestos centered wire gauze 54 being cut away to permit the passage between vertical bars 29 and 33. The function of the asbestos centered wire gauze 54 is to spread the heat given off by burner 20 in an even manner rather than focusing it on one point of beaker 18.

While I have shown in my example a form of a device for holding laboratory equipment such as beakers, my invention is not limited thereto but comprises all modifications of this device which are apparent to one skilled in the art. For example while the holding means were shown as consisting of three units the invention is not limited to this number but comprises any device embodying at least one of such units. Furthermore, while the holding leaves were shown as flat members they may be curved to conform to the shape of the laboratory vessel which is to be held in place. While the holding leaves in the present example were coil spring actuated they might be actuated by other forms of springs such as leaf springs, plate springs, conical helical springs and the like. Although the invention is preferably in the form shown the handles 50 and 51 may be dispensed with and a suitable attachment inserted in socket 8 in lieu of clamping means 12 or preferably in combination therewith to be used as a handle; or the handles 50 and 51 may be modified both as to their shape and insulation covering. Also while horizontal arcuate member 11 has been described as extending along the top extremity of the vertical bars it may be advantageously lowered, similarly clamping means 12 can also be relocated and median horizontal member 36 disposed with.

Furthermore notwithstanding that base 28 is preferably constructed as shown, suitable gauze and/or asbestos gauze or other heat scattering means may be incorporated directly into base 28 with the consequential dispensing of the use of asbestos centered wire gauze 54. Other variations readily apparent to the skilled mechanic such as the use of different construction materials for the present invention such as stainless steel, steel, Monel metal, iron, bronze, aluminum alloys and plastics; or locating the holding means in a different position; constructing the frame and base out of a single piece of metal or plastic and later punching suitable spaces therein; modifying the shape and size of detachable clamping means 12 etc. are considered to be encompassed in the present invention and covered in the appended claims.

The present invention may be used for beakers of differing sizes, the size of the beaker and the range of beaker sizes will determine the size of the present device. As previously stated the holding leaves may be curved or shaped to conform to other type laboratory vessels such as Florence flasks, Erlenmeyer flasks, bottles, flasks, test tubes, bowls, bulbs, crucibles, dishes, jars and the like. The ends of studs 38 and 42 may be threaded and suitably shaped leaves may be interchangeably screwed thereon. Through the use of the present invention, the operations of pouring, heating, stirring, and transporting laboratory vessels and their contents may be safely and securely carried out with the laboratory vessel and its contents visible at all times. Furthermore when dealing with explosive chemicals suitable wire gauze cutouts may be wrapped

around the frame of this device ensuring a great amount of protection for the laboratory technician in the event of an explosion.

I claim:

- 5 1. A device for holding laboratory apparatus comprising a base, a frame mounted on said base comprising spaced rigid vertical bars, said frame having an upper member joining said bars, handles attached to said vertical bars, a plurality of leaves, each of said leaves attached to a vertical bar by pin and spring means, said spring pressing each of said leaves therefrom whereby the laboratory apparatus is firmly retained in said holding device.
- 10 15. 2. A device for holding laboratory apparatus comprising a base, a frame mounted on said base comprising spaced rigid vertical bars, said frame having an upper member joining said bars, wherein said upper member is provided with a removed section, whereby a portion of said laboratory apparatus is exposed between said vertical bars, handles attached to said vertical bars, a plurality of leaves, each of said leaves attached to a vertical bar by pin and spring means, said spring pressing each of said leaves therefrom whereby the laboratory apparatus is firmly retained in said holding device.
- 20 25. 3. A device for holding laboratory apparatus comprising a base, a frame mounted on said base comprising spaced rigid vertical bars, said frame having an upper member joining said bars, handles attached to said vertical bars, a plurality of leaves, each of said leaves attached to a vertical bar by pin and spring means, said spring pressing each of said leaves therefrom whereby the laboratory apparatus is firmly retained in said holding device and said device being provided with an arm at right angles thereto adjustably attaching said device to an upright standard.
- 30 40. 4. A device for holding laboratory apparatus comprising a base, a frame mounted on said base comprising spaced rigid vertical bars, said frame having an upper member joining said bars, wherein said upper member is provided with a removed section, whereby a portion of said laboratory apparatus is exposed between said vertical bars, handles attached to said vertical bars, a plurality of leaves, each of said leaves attached to a vertical bar by pin and spring means, said spring pressing each of said leaves therefrom whereby the laboratory apparatus is firmly retained in said holding device and said device being provided with an arm at right angles thereto adjustably attaching said device to an upright standard.
